Primary Examiner — Patricia A Palasik(74) *Attorney, Agent, or Firm* — CBM Patent Consulting, LLC(57) **CLAIM**

The ornamental design for a gear-driven pellet mill, as shown and described.

DESCRIPTION

FIG. 1 is a top plan view of a gear-driven pellet mill showing my new design;

FIG. 2 is a front elevational view thereof;

FIG. 3 is an enlarged detailed view of the gear-driven pellet mill as shown in circle 3 of FIG. 2;

FIG. 4 is a rear elevational view thereof;

FIG. 5 is a left side elevational view thereof;

FIG. 6 is a right side elevational view thereof;

FIG. 7 is a perspective view thereof; and,

FIG. 8 is an enlarged detailed view of the gear-driven pellet mill as shown in circle 8 of FIG. 7.

The broken lines shown in the figures represent portions of the gear-driven pellet mill that form no part of the claimed design.
